DESIGN FOR A DRESS

Harry Goldman, New York, N. Y.

Application August 30, 1938, Serial No. 79,630

Term of patent 3½ years

To all whom it may concern:

Be it known that I, Harry Goldman, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

Figure 1 is a front view of a dress showing my new design.

Figure 2 is a rear view of the dress shown in Figure 1.

My design is characterized by the combination on the dress disclosed, of the specific tucks on the upper front and rear of the blouse and on the skirt and sleeves, substantially as shown.

I claim:

The ornamental design for a dress, substantially as shown and described.

HARRY GOLDMAN.
